CLAIM

The ornamental design for a display screen with graphical user interface, as shown and described.

DESCRIPTION

FIG. 1 is a front view of a display screen with graphical user interface according to a first embodiment of our new design; FIG. 2 is a front view of a display screen with graphical user interface according to a second embodiment of our new design; and, FIG. 3 is a front view of a display screen with graphical user interface according to a third embodiment of our new design. The dot-dash broken line illustrates a display screen and forms no part of the claimed design. The remaining evenly-dashed broken lines illustrate portions of the graphical user interface that form no part of the claimed design.

1 Claim, 3 Drawing Sheets
